No. 865,984.

PATENTED SEPT. 17, 1907.

J. F. APPLEBY.
COTTON PICKING MACHINE.
APPLICATION FILED AUG. 15, 1906.

UNITED STATES PATENT OFFICE.

JOHN F. APPLEBY, OF CHICAGO, ILLINOIS, ASSIGNOR TO DIXIE COTTON PICKER COMPANY, OF REDFIELD, SOUTH DAKOTA, A CORPORATION OF SOUTH DAKOTA.

COTTON-PICKING MACHINE.

No. 865,984.

Specification of Letters Patent.

Patented Sept. 17, 1907.

Application filed August 15, 1906. Serial No. 330,743.

To all whom it may concern:

Be it known that I, JOHN F. APPLEBY, a citizen of the United States, residing at Chicago, in the county of Cook and State of Illinois, have invented a certain 5 new and useful Improvement in Cotton-Picking Machines, of which the following is a full, clear, concise, and exact description, reference being had to the accompanying drawings, forming a part of this specification.

10 My invention relates to cotton picking machines, and has for its object the provision of an improved gearing governing the operation of the picking fingers thereof, the invention in its preferred embodiment being an improvement upon that class of machines disclosed in 15 my United States Patent No. 798,651, dated September 5—'06. In the said patent I have employed a spur pinion or gear fast upon each shaft of a picker column, which picker column is in gear with a plurality of picking fingers. This gear is adapted for in- 20 termittent (though, preferably indirect) driving connection with the segmental rack, that is preferably substantially stationarily mounted, this rack being so positioned that the driving connection thereof with said pinion and like pinions of other picker columns 25 is effected just before the picking fingers are thrust into the cotton bushes, so that the picking fingers are rotated while they are within the bushes, such rotation ceasing after the cotton picking fingers are withdrawn from the range of the bushes, owing to the separation of the driving connection between said pinions and said rack. In my said patent I have shown how 30 the picking fingers are prevented from rotation when they are not in driving connection with the segmental rack, there being shown in the said patent a delay ele- 35 ment for this purpose, which is concentric with the segmental rack and which affords a smooth peripheral track with which blocks fixed with respect to picker operating pinions, engage.

I found in practice that in the course of time the 40 blocks are liable to wear depressions near the entering end of the delay element in the peripheral track afforded thereby, and to overcome this objection I have provided a mounting, which while substantially permitting the delay element to be stationarily lo- 45 cated, also permits said delay element to yield when it is impinged upon by a block entering the track afforded thereby. This yielding action will prevent the wear that I have mentioned, and inasmuch as it is only the entering portion of the delay element which 50 is to be guarded against the impact of the entering blocks, I desirably form the said delay element in sections, one of which is preferably rigidly mounted, while the companion section, which is the entering section of the delay element, is permitted to yield 55 slightly. This entering section of the delay element

is desirably formed of very tough metal, such as chilled steel, so as still further to reduce the probability of wear.

I will explain my invention more fully by reference to the accompanying drawing, in which—

60

Figure 1 is a side view of so much of a cotton picking machine including the device of my invention as is necessary to an understanding of the invention. Fig. 2 is a sectional plan view on line 2 2 of Fig. 1. Fig. 3 is a sectional view on line 3 3 of Fig. 2. Fig. 4 is a 65 detail view of certain parts of the mechanism illustrated in Figs. 1 and 2.

Like parts are indicated by similar characters of reference throughout the different figures.

The invention is shown as applied to that type of 70 cotton picking machines which is primarily adapted to the picking of short staple cotton and in which the cotton picking fingers travel in vertical planes bodily longitudinally of the machine, though I do not wish to be limited to the precise type of machine in connection with which my invention has been illustrated.

75 Picker columns (portions 1 of which are indicated) are disposed horizontally, and each carries an operating shaft 2 that serves to drive the picking fingers 3, as will appear, the angular positions of these fingers being 80 determined by any suitable mechanism, such as that indicated in my aforesaid patent, and as such positioning means forms no novel part of my present invention, I will not further describe the same. Each picker shaft is provided with a pinion 4, that is driven by a 85 master pinion 5, each master pinion operating two pinions 4, there being thus grouped together three pinions as a unit and adapted for co-operative relation with the segmental gear 6. The pinion 5 is preferably a compound pinion desirably including a supple- 90

mental pinion element 7 fixed with respect to the element 5 and itself adapted to mesh or operatively engage the segmental gear 6. There are, thus, twice as many pinions 4 and twice as many picker columns as there are pinions 5. Each compound pinion 5, 7 95 has rigidly secured thereto an arresting block 8, which block, by engaging the peripheral track afforded by the delay element 9, serves to prevent rotation of the picking fingers until said block has left the delay element and has resumed its driving connection with 100 the segmental gear 6. The gearing 4, 5, 6 and 7 causes a very high rate of rotation of the picking fingers about their own axes without the employment of a large supplemental rack 6, by which mechanism a very compact construction may be contained within a small 105 space, all as set forth in my aforesaid patent.

110 As indicated in my aforesaid patent, the picker columns are bodily rotated in a direction corresponding to the direction indicated by the arrow in Fig. 1 in the accompanying drawing; that is, the picker columns

- travel bodily in a clockwise direction when viewed from the right hand side of the harvester, so that the axes of the fingers may occupy substantially fixed vertical positions while the harvester is traveling 5 ahead and the fingers are rotating in the bushes. After the fingers leave the bushes, the rotation thereof about their axes is prevented, which result is occasioned by the engagement of the blocks 8 with the smooth peripheral track afforded by the delay element 9, and 10 in order that there may not be such violent impact between the delay element and the blocks 8 as to cause wearing of the blocks 8, the said delay element is caused to yield. Inasmuch as this result is only needed upon the initial engagement of the blocks with 15 the delay element, said delay element is formed in sections, the section 9¹ being pivoted at 10 and having a spring backing 11, preferably formed of a coil spring having a rigid abutment 12 at one end, and pressing the section 9 outwardly at the outer end, the two sections being 20 so related that the section of the element companion to the section 9¹ will limit the outward movement of said section 9¹, so that the peripheral curve of the track may have a common center throughout. When a block 8 impinges upon the section 9¹, said section yields 25 sufficiently (and the extent of the yielding movement may be comparatively slight) to prevent the said block from injuring the section, which result is promoted by forming the section 9¹ of metal that will not readily wear.
- 30 It need hardly be stated that one of the purposes for stopping the rotation of the fingers about their axes, is to enable the cotton to be readily removed from said fingers.
- I have indicated a spring cushion 13 for the gear 35 6, so that said gear may slightly yield, but as this characteristic is broadly claimed in my United States Patent No. 788,812, dated May 2, 1905, I will not go into further details respecting the same, except to note that the spring 13 has engagement at one end with 40 the lug 14 provided upon the gear 6 and at the other end has engagement with the stationary abutment 15.
- In the claims I use the word "segmental" or "sectional" as applied to the operating rack 6, not meaning thereby to define the shape of said rack, but to imply 45 that the rack is not a continuous rack, or, in other words, that it is not in driving relation with the picking fingers throughout the range of travel of said fingers.
- While I have herein shown and particularly described the preferred embodiment of my invention, it is obvious 50 that changes may be made without departing from the spirit thereof, but,
- Having thus described my invention, I claim as new and desire to secure by Letters-Patent:—
1. A cotton picking machine including a plurality of 55 bodily traveling cotton picking fingers, gearing for effecting the rotation of said fingers about their own axes, and means for checking the driven elements of said gearing including a yieldingly mounted delay element, to check the axial rotation of said fingers.
- 60 2. A cotton picking machine including a plurality of bodily traveling cotton picking fingers, gearing for effecting the rotation of said fingers about their own axes, said gearing including a segmental or sectional rack, and gear elements affording driving connection between said rack and the fingers, and means for checking the driven elements of said gearing including a yieldingly mounted delay element to check the axial rotation of said fingers.
- 65 3. A cotton picking machine including a plurality of bodily traveling cotton picking fingers, gearing for effecting the rotation of said fingers about their own axes, said gearing including a segmental or sectional rack, and gear elements affording driving connection between said rack and the fingers, and means for checking the driven elements of said gearing including a yieldingly mounted delay element to check the axial rotation of said fingers, 70 each group of elements driven by the sectional rack being provided with a block that rides upon the delay element for the purpose stated.
4. A cotton picking machine including a plurality of bodily traveling cotton picking fingers, gearing for effecting the rotation of said fingers about their own axes, and means for checking the driven elements of said gearing including a delay element to check the axial rotation of said fingers, 75 said delay element being formed in relatively movable sections. 80
5. A cotton picking machine including a plurality of bodily traveling cotton picking fingers, gearing for effecting the rotation of said fingers about their own axes, said gearing including a segmental or sectional rack, and gear elements affording driving connection between said rack and the fingers, and means for checking the driven elements of said gearing including a delay element to check the axial rotation of said fingers, 85 said delay element being formed in relatively movable sections.
- 90 6. A cotton picking machine including a plurality of bodily traveling cotton picking fingers, gearing for effecting the rotation of said fingers about their own axes, said gearing including a segmental or sectional rack, and gear elements affording driving connection between said rack and the fingers, and means for checking the driven elements of said gearing including a delay element to check the axial rotation of said fingers, 95 said delay element being formed in relatively movable sections, each group of elements driven by the sectional rack being provided with a block that rides upon the delay element for the purpose stated.
- 100 7. A cotton picking machine including a plurality of bodily traveling cotton picking fingers, gearing for effecting the rotation of said fingers about their own axes, and means for checking the driven elements of said gearing including a delay element to check the axial rotation of said fingers, 105 said delay element being formed in relatively movable sections, one of said sections being yieldingly mounted.
- 110 8. A cotton picking machine including a plurality of bodily traveling cotton picking fingers, gearing for effecting the rotation of said fingers about their own axes, said gearing including a segmental or sectional rack, and gear elements affording driving connection between said rack and the fingers, and means for checking the driven elements of said gearing including a delay element to check the axial rotation of said fingers, 115 said delay element being formed in relatively movable sections, one of said sections being yieldingly mounted.
- 120 9. A cotton picking machine including a plurality of bodily traveling cotton picking fingers, gearing for effecting the rotation of said fingers about their own axes, said gearing including a segmental or sectional rack, and gear elements affording driving connection between said rack and the fingers, and means for checking the driven elements of said gearing including a delay element to check the axial rotation of said fingers, 125 said delay element being formed in relatively movable sections, one of said sections being yieldingly mounted, each group of elements driven by the sectional rack being provided with a block that rides upon the delay element for the purpose stated.
- 130 10. A cotton picking machine including a plurality of bodily traveling cotton picking fingers, gearing for effecting the rotation of said fingers about their own axes, said gearing including a segmental or sectional rack, and gear elements affording driving connection between said rack and the fingers, and means for checking the driven elements of said gearing including a delay element to check the axial rotation of said fingers, 135 said delay element being formed in relatively movable sections, one of said sections being yieldingly mounted, each group of elements driven by the sectional rack being provided with a block that rides upon the delay element for the purpose stated.
11. A cotton picking machine including a plurality of bodily traveling cotton picking fingers, gearing for effect-

- ing the rotation of said fingers about their own axes, said gearing including a segmental or sectional rack, and gear elements affording driving connection between said rack and the fingers, and means for checking the driven ele- 5 ments of said gearing including a delay element to check the axial rotation of said fingers, said delay element being formed in relatively movable sections, each group of elements driven by the sectional rack being provided with a block that rides upon the delay element for the purpose 20 stated, the section of the delay element that is first engaged to check the rotation of the fingers being yieldingly mounted.
- 10 12. A cotton picking machine including a plurality of bodily traveling cotton picking fingers, gearing for effecting the rotation of said fingers about their own axes, said gearing including a segmental or sectional rack, and gear elements affording driving connection between said rack and the fingers, and means for checking the driven ele- 15

ments of said gearing including a delay element to check the axial rotation of said fingers, said delay element being formed in relatively movable sections, each group of elements driven by the sectional rack being provided with a block that rides upon the delay element for the purpose 20 stated, the section of the delay element that is first engaged to check the rotation of the fingers being yieldingly mounted.

In witness whereof, I hereunto subscribe my name this 8th day of August A. D., 1906.

JOHN F. APPLEBY.
